SIGNAL TELEPHONE SYSTEM

William H. Waite, Lynbrook, N. Y., assignor to
 Dictograph Products Company, Inc., Jamaica,
 L. I., N. Y., a corporation of Delaware

Application April 1, 1933, Serial No. 663,940

18 Claims. (Cl. 179—40)

This invention relates to a signal telephone system especially adapted for use in hospitals, although the invention is not limited to this use. A telephone system of this type is disclosed in my prior Patent No. 1,841,771, dated January 19, 1932, and the present invention is an improvement on the invention described in the aforementioned patent.

The system of the present invention, like that of the aforementioned patent, includes a master station at the nurses' or central office, and a plurality of substations connected to the master station and located in the various patients' private rooms, adjacent the beds of patients in wards, or the like, and corresponding signal devices, such as lights or audible signals are located at the master station corresponding to the several substations, over or adjacent to the doors of the patients' private rooms, over or adjacent the beds of the patients in the wards, on their instruments, or the like, and pilot signals, preferably visual, are located at the heads of corridors, over the doors of the wards, or the like, to indicate that a patient in that particular corridor or in that particular ward is signaling. The improvement of the present invention resides principally in the arrangement of the circuits whereby the amount of necessary wiring is reduced to such a degree that the existing annunciator wiring in a hospital may be used without substantial change, and the former annunciator system converted into a telephonic system. For example, in the system of the aforementioned patent there are two individual wires for each substation and three common wires, whereas in the new system of the present invention there is only one individual wire for each substation and four common wires. Accordingly, in a typical installation having twenty substations, the system of the patent requires 43 wires and the new system of this invention requires only 24 wires, or approximately 55% of the total wiring, which considerably reduces the cost and size of the main cables, simplifies the installation of the system in new and existing hospitals, and permits the use of existing annunciator cable without substantial change in so far as the number of wires is concerned.

In the preferred embodiment of the invention, actuation of a substation signal button by a patient energizes a corresponding signal at the master station in the nurses' or central office and the pilot and door signals, and prepares the talking circuit for establishment by the nurse responding at the master station. In responding

to the signal, the nurse actuates a corresponding key, switch, or the equivalent, which deenergizes the master station and pilot signals and establishes the telephonic circuits between the nurse's and the patient's telephone instruments and the circuit is ready for communication between the nurse and the patient in response to the patient's original signal. Restoration of the nurse's switch opens the talking circuit, but the signals are maintained until the patient's button is released, which is locked in closed position after manipulation, so that the signals remain until responded to. An auxiliary audible signal is also preferably provided at the master station to call attention to a calling patient, but the signal does not remain energized when the button is locked closed, although it is energized each time the patient presses the locked button.

In a modified arrangement of the system of the present invention, the nurse at the master station, by throwing a switch, completes her talking circuit from her transmitter to the patient's loud speaker, so that the nurse may talk to the patient at any time and the patient may respond by pressing the corresponding button to complete the patient's talking circuit between the patient's transmitter and the nurse's receiver. This paging feature is a valuable adjunct in a hospital signaling system, for the reason that with it a supervisor may communicate with any and all of the patients in a short time without making many personal trips to the patients' private rooms or to the wards in accordance with the usual practice.

It will be seen that the present invention has all of the advantages of facilitated communication between the several patients and the nurse, which are incorporated in the system of the aforementioned patent, and has the additional advantages of simpler wiring, the paging feature, and other advantages which will be ascertained upon reference to the accompanying drawings, in which

Figure 1 is an electrical diagram of one form of the signal telephone system of this invention;

Figure 2 is a simplified schematic diagram of the telephonic circuits;

Figure 3 is a partial view of a modified form of the invention incorporating the paging feature; and

Figure 4 is a partial view of the new system illustrating the way in which it may be adapted to an existing annunciator system.

Referring to Figure 1 of these drawings, letters

A, B, C, D, E and F designate the substations in the various patients' private rooms in a hospital, or the several beds in a ward which is equipped with the substations mentioned. The letter M designates the master station in the nurses' office to which the several substations are connected.

The master station M in the nurses' office is equipped with a plurality of switches, keys, or the like, designated a, b, c, d, e and f, corresponding to the substations A, B, C, D, E and F, respectively. The master station M is also equipped with the visual signals a1, b1, c1, d1, e1, and f1, individual to the keys a, b, c, d, e and f, and corresponding to the substations A, B, C, D, E and F, respectively. These visual signals may be shutters or flags, as indicated, signal lights, or the equivalent, and are so arranged that when a flag is raised or a light illuminated it identifies visually the substation which is calling.

Each of the substations A, B, C, D, E and F is provided with a corresponding visual signal A1, B1, C1, D1, E1, and F1, which are located over or adjacent the doors of the corresponding patients' private rooms, over or adjacent the corresponding bed or on the instrument in the ward, or the like.

Also, located at the head of a corridor, wing, or section of patients' private rooms over or adjacent the door of a ward, or the like, is a visual signal in the form of a pilot lamp P, which indicates that a patient in that corridor or wing, section, ward, or the like, is signaling, and a nurse may then identify the particular patient who is signaling by his or her private lamp A1, B1, C1, D1, E1, or F1. As indicated in Figure 1, one of the pilot lamps P1 is individual to substations A, C, E, and the other pilot lamp P2 is individual to substations B, D, E, which in the particular arrangement illustrated, may be the way in which the private rooms are divided by the corridors, wings, or sections, or the way in which the substations are classified or arranged in wards, or the like.

The substations A, B, C, D, E and F are all alike and therefore the description of one of them, namely, substation A, will suffice for all. The substation includes a patient's receiver 10, which is preferably a loud speaker, a patient's transmitter 11, which is preferably a microphone, and a push button 12, which the patient depresses when he wishes to speak to the nurse at the nurses' office. The instruments enumerated may be mounted in or on a portable casing standing adjacent the patient's bed, or the like, and the push button may be conveniently placed at the end of a flexible cord so as to be available to the patient. The push button 12 locks in closed position after being pressed and remains in closed position until it is released. Any suitable type of locking button may be employed and for purposes of illustration a diagrammatic form of locking button is disclosed. This button includes a first contact 13 which is provided with an extension 65 which hooks under the abutment of a latch 14, so that the spring contact 13 is held down after the button 12 is pressed. Below the first spring contact 13 is a second spring contact 15, adapted to be engaged by first spring contact 13 and remain engaged therewith while latch 14 holds first contact 13 in closed position. Similarly, below second spring contact 15 is a third spring contact 16, adapted to engage therewith; below third spring contact 16 is a fourth spring contact 17, adapted to engage with the former, and below the fourth

spring contact 17 is a fifth spring contact 18, adapted to engage with the former. The fifth spring contact 18, however, does not remain engaged with fourth spring contact 17 when the first spring contact 13 is held locked in closed position by latch 14, although all of the other spring contacts are in mutual engagement. Fifth spring contact 18 is only engaged with fourth spring contact 17 when the button 12 is depressed below the point at which the latch 14 engages it. Thus, when the patient presses button 12 all of the spring contacts, including fifth spring contact 18 are in engagement, but when the patient releases pressure on button 12, fourth spring contact 17 becomes disengaged from fifth spring contact 18, although the latch holds the first, second, third and fourth spring contacts 13, 15, 16 and 17, respectively, in engagement. The purpose of this arrangement will be described later.

First spring contact 13 is connected by wire 19 to a contact 20 normally engaged with armature 21 of relay 22, and armature 21 is in series with patient's microphone 11, which is connected by wire 23 to the talking wire 24 of the main cable of the system.

The second spring contact 15 is connected by wire 26 to relay 22, the other terminal of which is connected by wire 27 to switch contact 28 of key a, and this contact is normally engaged with contact 29 connected by wire 30 to the relay 31 of signal flag a1, and the other terminal of this relay is connected to wire 32, which in turn is connected to the positive line wire 33 of the main cable, which is connected to the corresponding pole of signal battery 34, the negative terminal 35 of which is connected to negative line wire 35 of the main cable. The patient's loud speaker 10 is connected in parallel with the relay 22 and one of the leads of the loud speaker 10 contains the condenser 36, the purpose of which will be described later.

The armature 31 of flag relay 31 is adapted to engage spring contact 38 when the relay 31 is energized to close a circuit leading from positive line wire 33, wire 32, spring contact 38, armature 37 of flag relay 31, wires 40 and 41, pilot lamp P1 and negative line wire 35.

The third spring contact 16 of the patient's push button switch is connected by wire 42 to the corresponding door, bed or instrument lamp A1, which is connected by wire 43 to positive line wire 33.

The fourth spring contact 17 of the patient's push button switch is the negative feed for the push button and is connected by wire 44 to negative line wire 35.

The fifth spring contact 18 of the patient's push button switch is connected by wire 46 to line wire 47, which is the audible signal wire of the main cable and is connected by wire 47' to the audible signal 48 at the master station, which may be in the form of a buzzer, or the like, the other side of which is connected through disconnect switch 49 by wire 50 to the positive line wire 33. The use of the buzzer 48 depends upon requirements, and it may be omitted if not required and thus one of the line wires of the main cable will be eliminated, namely, wire 47.

Each of the other substations B, C, D, E and F, is provided with an individual wire 27 corresponding to wire 27 to substation A, this wire being connected to the corresponding key at the master station, and the other wires 23', 44' and 46' leading from the remaining substations, B,

C, D, E and F, correspond to wires 23, 44 and 46 of the substation A just described.

Spring contact 51 cooperating with common contact 28 of nurses' station key *a*, which is normally disengaged from common contact 28, is connected by wire 52 to the nurse's transmitter 53, the other pole of which is connected by wire 54 to spring contact 55, adapted to engage contact 56, which is connected by wire 57 to the positive terminal of talking battery 58, the negative pole of which is connected to negative line wire 35 of the main cable.

Joined to spring contact 55 of nurse's key *a* by an insulating block 59, so as to move therewith, is a second spring contact 60, which is connected by wire 61 to wire 24 of the main cable and which is adapted to engage spring contact 62 which is connected by wire 63 to nurse's receiver 64, the other terminal of which is connected to the positive pole of talking battery 58 through resistance 65. A second resistance 66 is connected across the terminals of the nurse's receiver 64. A talking impedance coil 67 is interposed between negative line wire 35 and nurse's microphone 53.

The telephonic circuit just described is shown in the simplified schematic diagram of Figure 2 in which the winding of relay 22 is represented as an impedance across the terminals of the patient's loud speaker 10. The connections of the switch, telephonic instruments and signal devices corresponding to other substations are identical to those described in connection with substation A and therefore they need not be further described.

In operation, assuming that the patient at substation A presses push button 12 to signal a nurse at the central office, several circuits are completed, one of which includes the buzzer 48 in the central office, this circuit being traceable from signal battery 34, by positive line wire 33, wire 50, buzzer disconnect switch 49, buzzer 48, wire 47, buzzer line wire 47, wire 46, fifth push button spring contact 18, fourth push button spring contact 17, wire 44, negative line wire 35 and back to battery 34. When the patient releases pressure on push button 12 the fourth spring contact 17 disengages fifth buzzer spring contact 18 to deenergize the buzzer 48, but the remaining spring contacts remain mutually engaged because latch 14 holds them in engagement in the manner illustrated in Figure 1. Subsequent pressure by the patient on button 12 reenergizes buzzer 48 for as long a period of time as the patient maintains the button 12 depressed. If the patient presses the push button 12 insistently, the nurse may silence the buzzer by opening the disconnect switch 49.

Engagement between third and fourth push button contacts 16 and 17, respectively, establishes a circuit from negative contact 17, contact 16, wire 42, door lamp A1, and positive line wire 33. The door lamp A1 over the door of the private room of the patient who signaled is accordingly illuminated to indicate to the nurse which patient is calling, if the nurse happens to be out of her office, it being understood that the lamp A1 may be over the bed of a calling patient in the ward, or the like.

Engagement between second and third contacts 15 and 16, respectively, establishes a circuit from negative contact 17 through contact 16, contact 15, wire 26, relay 22, wire 27, closed contacts 28 and 29 of key *a* at the nurse's station M, wire 30, relay 31, wire 32 and positive line wire 33. Energization of relay 22 breaks the normal circuit of the patient's transmitter or microphone 11 by dis-

engaging armature 21 from contact 20. Since this action takes place substantially simultaneously with the closing of the circuit of the patient's transmitter or microphone 11 by manipulation of the patient's push button 12, the patient's talking circuit practically remains deenergized.

Energization of flag relay 31 causes it to attract its armature 37 and raise flag or shutter *a* to designate to the nurse at the master station M that the patient at substation A is signaling. At 10 the same time armature 37 engages contact 38 to close a circuit from negative line wire 35, pilot light P1, wire 41, contacts 37 and 38, wire 32, and positive line wire 33. The illumination of pilot lamp P1 indicates to a nurse, if she is not in her office, that a patient in the corresponding corridor, wing, ward, or section of the hospital is calling and she may then, by glancing at the door or bed lamps A1, C1, and E1, ascertain which of the patients is calling, it being the patient at 20 substation A1 in this particular instance.

At the master station M the nurse, having been notified by the sounding of buzzer 48 that a patient is calling, glances at the master station instrument and identifies the patient because of the display of flag or shutter *a*. She then manipulates the key *a*, which breaks the normal connection between contacts 28 and 29 and makes contact between contacts 28 and 51, 55 and 56, and 60 and 62. The disengagement of contacts 28 and 29 deenergizes flag relay 31 so that flag *a* drops to break the contact between armature 37 and contact 38 and extinguish pilot lamp P1. The disengagement of contacts 28 and 29 also deenergizes relay 22, which accordingly releases its armature 21 so that the latter reengages contact 20 to remake the circuit of patient's transmitter or microphone 11, which is traceable from negative contact 17, contacts 16, 15 and 13, wire 19, contacts 20 and 21, transmitter or microphone 11, wire 23, line wire 24, wire 61, contacts 60 and 62 of key *a*, wire 63, nurse's master station receiver 64, resistance 65, wire 51 to talking battery 58, thus establishing the patient's talking circuit.

Engagement between contacts 55 and 56 and 45 of contacts 28 and 51 of key *a* establishes two circuits, one traceable from talking battery 58 through wire 57, contacts 56 and 55, wire 54, transmitter 53, wire 52, impedance 61, line wire 35 back to talking battery 58 and a circuit in shunt with impedance 61 traceable through wire 52, contacts 51 and 28, wire 27, loudspeaker 10 and blocking condenser 36 shunted by relay 22, wire 26, contacts 15, 16, 17, wire 44, line wire 35. Although relay 22 is now in the energized circuit of talking battery 58 the voltage applied to relay 22 is insufficient to operate it so that armature 21 and contact 20 remain in engagement. The patient's listening circuit is accordingly established and communication between the patient and the nurse at the master station may begin.

As indicated in the schematic diagram of Figure 2, the impedance 61 is in the nurse's talking circuit and the talking voltage developed across this impedance is impressed upon the patient's loud speaker 10 through the blocking condenser 36, the impedance of the patient's relay 22 being sufficiently high to shunt all talking voltages through the loud speaker 10. The blocking condenser 10 serves to shunt current from signal battery 34 through patient's relay 22 when the patient's pushbutton 12 is pressed, thus energizing relay 22. The patient's relay 22 renders the system selective, for if this relay were not pres- 75

ent, all microphones of the other patients' substations whose pushbuttons were operated would be connected to the nurse's receiver, so that the latter could hear any noises in the rooms of the other patients.

Upon completion of the conversation between the patient and the nurse, the latter restores key *a* to its initial position, which disconnects the circuits to the nurse's transmitter 53 and receiver 54 and, by the reclosure of contacts 28 and 29, patient's relay 22 and flag relay 31 are reenergized separating armature 21 from contact 20 on patient's relay 22 and reenergizing pilot lamp *P* through the closing of contacts 37 and 38 on flag relay 31, unless the patient has reopened the locking button in the meantime by releasing the latch 14, whereupon all circuits are reopened including the circuit of relay 22, which accordingly releases armature 21 to reengage contact 20 and prepare the normal circuit through patient's transmitter or microphone 11 for completion by subsequent manipulation of the patient's button 12. The door lamp *A* and the corresponding pilot lamp *P* are also extinguished when their corresponding contacts 16 and 37-38, respectively, are open. The system is now restored to its original condition for reoperation by any one of the substations in the manner described.

Incorporation of the paging features, whereby the nurse at the master station may talk to the patient at any time without awaiting a signal from the patient, is simply made by changing the connections of the patient's loud speaker 10. Instead of connecting the patient's loud speaker 10 directly in parallel with the relay 22, as in the arrangement illustrated in Figure 1, it is bridged across wires 27 and 44, as illustrated in Figure 3. With this arrangement the nurse at the master station simply throws key *a* to establish two circuits, one from talking battery 58 through wire 51, closed contacts 56 and 58, wire 54, master station transmitter 53, impedance 67, wire 35 back to talking battery 58, and the other from impedance 67 through wire 52, key contacts 51 and 28, wires 27 and 70, patient's loud speaker 10, blocking condenser 36, and wires 71, 44 and 35, back to the other side of impedance 67 thus establishing a talking circuit between the nurse's transmitter 53 and the patient's loud speaker 10 without any previous preparation of the circuit by the patient or the display of signals.

Manipulation of the nurse's key also prepares the patient's talking circuit to the nurse's receiver 64 from talking battery 58, resistance 65, receiver 64, wire 63, key contacts 62 and 60, wires 61, 24 and 23, patient's microphone 11, closed contacts 21 and 20, wire 19, and open contacts 13, 15, 14 and 17. This circuit, i. e., the patient's talking circuit, may be completed by the patient upon manipulation of his button 12 in the manner described.

Manipulation of the patient's button 12 does not, in this instance, break the circuit to the patient's microphone 11 because relay 22 remains deenergized, due to the disconnection between key contacts 28 and 29 resulting from manipulation of the nurse's key *a*.

In this way a nurse at the master station may page all of the patients without making it necessary for the nurse to make personal trips to the various patients' rooms. This is a valuable adjunct to a hospital communication system, since in many instances it is desirable for the nurse to locate a doctor or to communicate with the patient without leaving the nurse's station.

In existing hospitals which are equipped with the standard annunciator system, the original wires of the annunciator system may be used for converting the system into a telephone system in accordance with the present invention without disturbing the annunciator cables in any way except to make connections at the open ends thereof. This arrangement is illustrated diagrammatically in Figure 4, in which the original annunciator 72 fitted with signals such as lamps A2, B2, C2, D2, E2 and F2, corresponding to the patients' rooms, beds, or the like, A, B, C, D, E and F, respectively, is employed instead of the flag signals *a* at the master station. These lamps or other signals are connected in the circuits of the nurse's corresponding keys to take the place of the flags *a*, illustrated in the arrangement of Figure 1. For example, the contact 29 of each of the nurse's keys *a*, *b*, *c*, *d*, *e* and *f* is connected to the corresponding lamp or other signal of the annunciator 72, the remaining connections of the circuit being the same as illustrated in Figure 1 and may include the buzzer 48, although this audible signal is not shown in Figure 4.

With this arrangement, manipulation of the patient's button 12 at substation A, for example, closes a circuit from positive line wire 33 to the annunciator 72 through wire 73, annunciator lamp or other signal A2, wire 30', normally engaged contacts 29 and 28 of master station key switch *a*, wire 27, substation relay 22 and patient's loud speaker 10, wire 26, patient's button second contact 15, third contact 16, fourth contact 17, wire 44 and negative line wire 35. The resultant energization of annunciator signal A2 identifies the calling patient at substation A, and the nurse responds as before, by manipulating corresponding key *a* at the master station.

It will be seen that annunciator wires take the place of line wires 24, 33 and 47 and the individual substation wires 27, and since the annunciator wires are already installed in existing cables of the hospital, rewiring of the hospital becomes unnecessary, and the attendant labor, noise, and excavation of the walls or floors of the hospital to lay the line wires or cables are eliminated.

It will be seen that the new telephone signal system of this invention, although extremely simple and employing a minimum number of wires and other parts, is nevertheless absolutely selective, whereby communications between the master station and the individual patients remain private. With the paging feature the nurse at the master station may throw the key corresponding to the patient to whom she wishes to speak and talk to the patient at any time and the patient may answer by pressing the button 12 and talking.

While the system of the present invention has been illustrated and described as being particularly adapted for use in hospitals, it is to be understood that its utility is not limited to this purpose, but the system may be employed wherever an intercommunicating telephone system of simple construction is desired. Also, while a preferred embodiment of the invention has been illustrated, it is also to be understood that the invention is not limited thereby, but is susceptible to changes of form and detail within the scope of the claims.

I claim:

1. In a telephone system, the combination of a master station having a telephone instrument, a plurality of substations each having a telephone instrument, a plurality of common conductors each connected to said substation and to the

- master station, and only one wire between each substation instrument and the master station instrument which is individual only to those instruments.
5. In a telephone system, the combination of a master station having a telephone instrument, a plurality of substations each having a telephone instrument, a plurality of common conductors each connected to each substation and to the master station, only one wire between each substation instrument and the master station instrument which is individual only to those instruments, and a switch in each single wire for connecting and disconnecting the corresponding substation instrument with the master station instrument.
3. In a telephone system, the combination of a master station having a telephone instrument, a plurality of substations each having a telephone instrument, a plurality of common conductors each connected to each substation and to the master station, only one wire between each substation instrument and the master station instrument which is individual only to those instruments, and a switch at the master station corresponding to each substation and connected in the single wire thereof for connecting and disconnecting the corresponding substation instrument with the master station instrument.
4. In a telephone system, the combination of a master station having a telephone instrument, a plurality of substations each having a telephone instrument, a plurality of common conductors each connected to each substation and to the master station, only one wire between each substation instrument and the master station instrument which is individual only to those instruments, and a switch at each substation connected in the single wire thereof for connecting and disconnecting the corresponding substation instrument with the master station instrument.
5. In a telephone system, the combination of a master station having a telephone instrument, a plurality of substations each having a telephone instrument, a plurality of common conductors each connected to each substation and to the master station, only one wire between each substation instrument and the master station instrument which is individual only to those instruments, a switch at the master station corresponding to each substation and connected in the single wire thereof, and a switch at each substation connected in the single wire thereof, the master station and substation switches being adapted to connect and disconnect the corresponding substation instruments with the master station instrument.
6. In a telephone system, the combination of a master station having a telephone instrument, a plurality of substations each having a telephone instrument, a plurality of common conductors each connected to each substation and to the master station, one wire between each substation instrument and the master station instrument which is individual only to those instruments, a relay in the single wire of each substation, a second telephone instrument at each substation controlled by the corresponding relay, and a switch in each single wire for operating the corresponding relay.
7. In a telephone system, the combination of a master station having a telephone instrument, a plurality of substations each having a telephone instrument, a plurality of common conductors each connected to each substation and to the master station, one wire between each substation instrument and the master station instrument which is individual only to those instruments, a relay in the single wire of each substation, a second telephone instrument at each substation controlled by the corresponding relay, and a switch at the master station for operating the corresponding relay.
8. In a telephone system, the combination of a master station having a telephone instrument, a plurality of substations each having a telephone instrument, a plurality of common conductors each connected to each substation and to the master station, one wire between each substation instrument and the master station instrument which is individual only to those instruments, a relay in the single wire of each substation, a second telephone instrument at each substation controlled by the corresponding relay, and a switch at each substation for operating the corresponding relay.
9. In a telephone system, the combination of a master station having a telephone instrument, a plurality of substations each having a telephone instrument, a plurality of common conductors each connected to each substation and to the master station, one wire between each substation instrument and the master station instrument which is individual only to those instruments, a relay in the single wire of each substation, a second telephone instrument at each substation controlled by the corresponding relay, and switches at the substations and the master station for operating the corresponding substation relays.
10. In a telephone system, the combination of a master station having a telephone instrument, a plurality of substations each having a telephone instrument, a plurality of common conductors each connected to each substation and to the master station, one wire between each substation instrument and the master station instrument which is individual only to those instruments, a relay in the single wire of each substation, a second telephone instrument at each substation controlled by the corresponding relay, a switch in each single wire for operating the corresponding relay, and a second telephone instrument at the master station connectible to the second instrument at a substation upon operation of the corresponding switch.
11. In a telephone system, the combination of a master station having a telephone instrument, a substation having a telephone instrument, a normally closed circuit for at least one of said telephone instruments, a switch at the substation for breaking the normally closed circuit of said one telephone instrument, and a switch at the master station for restoring the circuit of said one telephone instrument and establishing a talking circuit between the master and said substation instruments.
12. In a telephone system, the combination of a master station having a telephone instrument, a plurality of substations each having a telephone instrument, a normally closed circuit for each substation instrument, a switch for breaking the normally closed circuit of the instrument at one of the substations, and a second switch for restoring the circuit of the instrument at the said one substation and establishing a talking circuit between the master and said substation instruments.
13. In a telephone system, the combination of a master station having a telephone instrument, a plurality of substations each having a tele-

- phone instrument, a normally closed circuit for each substation instrument, a switch at each substation for breaking the normally closed circuit of the corresponding telephone instrument, and a second switch at the master station for restoring the circuit of the instrument at the said one substation and establishing a talking circuit between the master and said substation instruments.
10. 14. In a telephone system, the combination of a master station having telephone instruments, a plurality of substations having telephone instruments, a normally closed circuit for each substation instrument, a switch at each substation for breaking the normal circuit of at least one of the corresponding substation instruments, and a switch at the master station for restoring the normal circuit of said one substation instrument and establishing a communication circuit between the said master station and substation instrument.
15. 15. In a telephone system, the combination of a master station having telephone instruments, a plurality of substations having telephone instruments, a switch at the master station for establishing a communication circuit to one of the instruments of a substation and preparing a second communication circuit to another instrument at the last-named station, and a switch at the said last-named substation for completing the said second communication circuit.
20. 16. In a telephone system, the combination of a master station having telephone instruments, a plurality of substations having telephone instruments, a switch at the master station for establishing a communication circuit only between the master station transmitter and a substation receiver, a second switch at the master station for preparing a second communication circuit between the master station receiver and the transmitter of the said substation, and a switch at the said substation for completing the said second communication circuit.
25. 17. In a telephone system, the combination of remote stations each having telephone instruments, a switch at one station for establishing a communication circuit between one of the instruments thereof and the corresponding instrument at another station, a second switch at said one station for preparing a communication circuit between the other instrument thereof and the corresponding instrument at said other station, and a switch at the said other station for completing at will the said second communication circuit.
30. 18. In a telephone system, the combination of a master station having telephone instruments, a plurality of substations each having telephone instruments, a switch at each substation for preparing a communication circuit to the master station, a switch at the master station for completing the said communication circuit to the corresponding substation, a second switch at the master station for preparing a second communication circuit to the last-named substation, and a second switch at the said last-named substation for completing the second communication circuit.
